UNITED STATES PATENT OFFICE.

JOHN HENRY DANIELS, OF ST. LOUIS, MISSOURI.

COMBINATION-TOOL.

No. 827,426.

Specification of Letters Patent.

Patented July 31, 1906.

Application filed May 10, 1905. Serial No. 259,849.

To all whom it may concern:

Be it known that I, JOHN HENRY DANIELS, a citizen of the United States, residing at 1325 North Whittier street, St. Louis, State of Missouri, have invented new and useful Improvements in Combination-Tools, of which the following is a specification.

This invention relates to a combination-tool, the invention comprising in general a handsaw so constructed that the blade may be adjusted to different positions for more convenient operation, according to the character of the work to be done, and also so that the saw may be folded or collapsed in order to permit it to be more readily carried in the pocket or packed in a tool-chest, the blade, further, being constructed to provide a screw-driver bit which is presented for use when the saw is collapsed in such a manner that the saw-handle may be employed for driving purposes, thus producing a tool which possesses a wide range of usefulness.

The object of the invention is to provide a tool embodying these characteristics and which is efficient in operation and susceptible of manufacture at a low cost.

The preferred form of the invention is illustrated in the accompanying drawings, in which—

Fig. 1 is a side view of my improved combination-tool, showing the blade adjusted for use as an ordinary compass-saw. Fig. 2 is a similar view showing the tool collapsed to fold the blade and project the driving-bit. Fig. 3 is a view in front elevation with parts arranged as in Fig. 1. Fig. 4 is a transverse section on line 4-4 of Fig. 1. Fig. 5 is a detail view of the butt-end of the saw.

Referring now more particularly to the drawings, the numeral 1 designates the handle, and 2 the blade, of the saw, the saw being of the hand type, commonly known as a "compass saw."

In accordance with my invention the handle 1 is constructed of two side pieces 3 and 4, each comprising a stock portion 5, forming a grip, a forwardly-projecting cheek-piece 6, and an intermediate connecting portion 7, each of said pieces 3 and 4 being composed, preferably, of a single metallic casting, although it may be made of any suitable material and in sections, if desired. The side pieces 3 and 4 are held spaced by a distance piece or filler 8, disposed between their connecting portions 7, the two side pieces and distance-piece being firmly united by rivets or other

suitable fastenings 9. This construction provides a handle whose gripping-stock portion and cheek-pieces or saw-receiving portion are spaced to form receiving-slots 10 60 and 11.

The blade 2 is enlarged or thickened at its butt-end, as indicated at 12, and reduced to form a screw-driver-bit portion 13, the enlargement of the butt providing for the 65 formation of a bit of proper thickness and strength to withstand the driving strain and also providing for the formation of a pivot-receiving opening 14 and a series of dowel seats or recesses 15 of proper depth between 70 the pivot-opening and driver-bit, said seats 15 extending transversely of the butt of the blade and on a slight arc concentric with the opening 14.

The butt portion 12 of the blade fits in the 75 slot 11 between the two cheek-pieces 6 and is pivotally connected thereto by a pivot pin or rivet 16, passing through the cheek-pieces and the opening 14, the pivot of the blade thus being so arranged and the cheek-pieces being 80 of such length that when the blade is disposed in operative position, as shown in Fig. 1, the bit 13 will be inclosed and concealed between the rear ends of the cheek-pieces.

One of the cheek-pieces 6 is formed in its 85 outer face with a concavity 17 and a screw-threaded transverse opening 18, communicating therewith, said opening receiving a locking-screw 19, having a milled operating-head 20, which lies within the recess 17, and 90 a reduced portion or dowel-pin 21, which projects inwardly beyond said opening and is adapted to engage any one of the series of seats 15, formed in the butt of the blade. The inner end of the screw 19 is adapted to 95 bear against the blade and to clamp it in position and to seat the dowel in the registering recess to rigidly lock the blade to the handle. By thus constructing the screw and blade it will be apparent that the blade 100 may be adjusted on its pivot 16 to bring any one of the dowel-seats 15 into alinement with the dowel-pin 21, so that by the proper adjustment of the blade and tightening of the screw the blade may be locked at different 105 positions relatively to the handle to adapt the saw to be more conveniently operated, according to the character of the work to be performed. The described mode of mounting the blade also permits the saw to be collapsed or folded, so that it may be more 110 readily carried in the pocket or packed in a

tool-chest. By loosening the screw 19 to release the dowel-pin 21 from the dowel-seat 15, with which it is engaged, the saw 2 will be left free to swing upon its pivot and, as 5 shown in Fig. 2, may be swung downwardly and rearwardly into the slot 10 in the stock portion of the handle, so as to lie between the cheek-pieces and stock portion, thus folding the saw in small compass for the de-
scribed purposes. When the blade has been 10 so adjusted, it may be clamped in position by tightening up the screw 19. This susceptibility of adjustment of the blade also provides for the projection of the screw-driver 15 bit 13, as it will be seen that when the blade is folded, as in Fig. 2, the bit 13 will be thrown forwardly of the cheek-pieces 6, thus enabling it to be used for driving or extracting a screw. The toothed edge of the blade 20 when folded is held beneath the lower edge of the distance-piece 7, so that it will not come in contact therewith, and this disposition of the blade permits the stock portion of the handle to be used as a grip in employing 25 the screw-driver bit.

Having thus described the invention, what is claimed as new is—

In a tool of the character described, the combination of a handle comprising slotted 30 stock and tool supporting portions arranged substantially at right angles to each other, said stock and tool supporting portions being joined by an arched connection and having 35 their upper portions arranged substantially in the same plane and coincident with the upper portion of the arched space therebe-

tween, a straight saw-blade having a thickened butt-end provided with an opening and a series of dowel-seats in rear of and concentric with said opening, the rear end of the 40 butt terminating in a screw-driver point, a pivot-pin passing through the supporting portion and opening in the blade and pivotally connecting the latter thereto, and a screw mounted upon the supporting portion 45 and having a dowel projection to engage said dowel-seats to hold the saw-blade at different angles of adjustment with respect to said supporting portion, the construction being such that when the blade is arranged in op- 50 erative position the screw-driver point will be concealed within the slot of the supporting portion and also such that the blade may be swung downwardly and rearwardly to project through and fold within the slotted 55 stock, whereby, owing to the described ar- 60 rangement of the parts, the blade when folded will extend longitudinally substantially in the plane of the supporting portion and will cross the arched space, thus project- 65 ing the screw-driver point so that the driving strain in operation will be sustained by the pivot-pin, and the concaved side of the arched union and back edge of the saw projecting across the arched space may be utilized as a grip in the screw-driving operation.

In testimony whereof I affix my signature in presence of two witnesses.

JOHN HENRY DANIELS.
